PAPER FASTENER

Clarence Still Lynch, New Hyde Park, N. Y.

Application February 10, 1949, Serial No. 75,601

4 Claims. (Cl. 24—153)

1

The present invention provides a paper fastener of the type adapted to conveniently secure or bind a stack of papers, and more particularly is concerned with a paper file fastener wherein a substantially U-shaped fastener including a base bar has its prongs or arms first threaded through the sheets of said stack and then through the aligned spaced slots in a retaining member or compressor, after which the prongs are folded down against the compressor and appropriately locked by suitable means cooperating with the compressor for securely holding the intervening stack between the base of the fastener and the compressor.

In practice, it has been customary to pile one sheet of paper upon another to form an intervening stack to be bound. However, the height of the stack is limited by the length of the foldable prongs. During appreciable accretions to the stack, the papers or records to be bound or fastened, often exceed the capacity of the prongs, and the user is left with the alternative of either starting a new file by utilizing another fastener to secure the accretions, or removing the fastener from the stack and substituting another fastener therefor having prongs of a length much longer than the length of the prongs of the fastener originally employed. In practice, these alternative methods have proved unsatisfactory. In the first case, one set of records becomes divided and is bound in several units or stacks. In the second case, extra time and labor are needed to substitute a new fastener having longer prongs.

Accordingly, one of the principal objects of the present invention is to eliminate the foregoing objections by providing fasteners of the above indicated type wherein an assembly may be built up by interlocking the prongs of one fastener with the base bar of the next fastener, which defines the retaining or compressor bar for the accumulated stack of papers, there being thus provided an additional length of prongs serving as retaining means for additional accretions to the stack.

A further object of the invention is to provide a construction of fasteners of the above indicated type which eliminates the need for removing one fastener and replacing it with one with longer prongs, and also eliminates the inconvenience of a previously suggested fastener construction having prongs which may be extended by mounting additional sections on the prongs for lengthening the capacity thereof, such arrangement being awkward and increasing materially the cost of the fasteners.

2

A further object of the invention is to provide a novel form of interlockable fastener which does not depart greatly from the usual type, and therefore eliminates increased cost while enabling the capacity of the fastener assembly to be increased readily any desired plurality of times and to any desired extent.

A still further object of the invention is to provide means whereby the capacity of the file fastener may be increased at any time without disturbing or removing any of the sheets then held by the fastener.

Another important object of this invention is the provision of a strap-like paper fastener including a pronged base plate or bar so designed as to successively and interlockingly bind together superimposed units of paper and to eliminate the necessity of using separate binding plates or bars, except with respect to the topmost unit, the base plate constituting a combined base plate and binding or compression plate.

Further objects of the invention will become apparent as the description proceeds, and the features of novelty will be pointed out in particularity in the appended claims.

The invention will be understood more readily from reference to the accompanying drawings, in which:

Fig. 1 is a side elevation of an improved file fastener embodying the features of the present invention.

Fig. 2 is a plan view of a binding plate or bar for the fastener of Fig. 1.

Fig. 3 is an end elevation of the fastener of Fig. 1, the view being taken on the line 3—3 of Fig. 1, looking in the direction of the arrows.

Fig. 4 is a transverse sectional elevation of the fastener taken on the line 4—4 of Fig. 1, looking in the direction of the arrows.

Fig. 5 is a side elevation showing an interlocked assembly of the improved fastener of the invention, showing the manner of interlocking the fasteners for increasing the capacity thereof.

Fig. 6 is a plan view of the binding plate of Fig. 5 in binding position.

Fig. 7 is an enlarged detailed fragmentary side elevation of one end of the fastener.

Fig. 8 is a fragmentary bottom view of Fig. 7, taken on the line 8—8 thereof.

Referring more particularly to the drawings, the improved file fastener of the present invention is composed of standard units or parts which can be made on one production machine or die, namely, the fastener member A and the binding or compression plate B. The fastener member

A comprises a base plate or bar 1 provided with the longitudinally extending side members 2 and 3, forming a top groove 4 and bottom grooves 5. The bar 1 is similarly off-set at adjacent end portions, as indicated at 6 and 7, to form stops for preventing accidental disengagement of the securing slide members 8 and 9 from the base bar 1. The ends of the base bar are formed with flexible loop portions 10, 11, that are integrally extended into prongs 12, 13, that are adapted to enter perforations 14, 15 in a stock or unit b of papers 16 in the usual manner for holding the individual papers of the stack. Adjacent to each prong and in the off-set end portions 6 and 7, the base bar 1 is provided with apertures 17, 18, which are adapted to receive the prongs 12 and 13 of a similar fastener which are threadable therethrough, as and for a purpose directly more fully appearing.

The binding plate B (Fig. 2) is provided with the longitudinally extending side members 2a and 3a, a top groove 4a and bottom grooves 5a, the prong receiving apertures 17a and 18a, and the slide members 8a and 9a, similar to the corresponding parts of base plate 1 of fastener A.

When the capacity of one pair of prongs 12 and 13 of a fastener A is filled, a second fastener A is placed on top of the stack b of the papers 16, the base plate or bar 1 thereof forming a binding member or compressor bar for said stack b, the free ends of the prongs 12 and 13 of the filled fastener A extending through apertures 17 and 18 of the superimposed second base bar 1 and are bent over into groove 4 and retained therein by the slides 8 and 9. The capacity of the second fastener A constitutes the second stack or unit c, and on which is placed over the free ends of the prongs 12 and 13 of the second fastener A, the base bar 1 of a third fastener A, with the protruding ends of said prongs bent over and secured by members 8 and 9 of the third fastener A. The filled third fastener A constitutes the topmost stack or unit d and on which is placed the binding or compressor plate or bar B with the free ends of the filled prongs extending through openings 17a and 18a, bent over into groove 4a and secured by the slide members 8a and 9a (Figs. 5 and 6) and which completes the unitary binding of the stacks or units b, c, and d, of the assembly shown in Fig. 5.

It will be seen, therefore, that in effecting a unitary binding of the stack capacity of a plurality of fasteners, that each fastener is a one-piece unit, the usual separate locking and compressor bar being eliminated by the combined base and binding bar members of the respective fasteners A, with the exception of the topmost stack, where the separate compressor bar B is used.

While from the above description it is apparent that the use of the binding plate or bar B is only necessary in binding a file where it does not exceed the capacity of a single fastener A for stack b, or the topmost stack d of a plurality of stacks when bound into a unitary structure by the interlocking of the component fasteners A. It will be further apparent, that if desired, the use of the binding plate or bar B may be completely eliminated by substituting therefor the base plate 1 of a fastener A placed on the topmost stack similar to stack b with the protruding ends of the prongs 12 and 13 extending through openings 17 and 18 and bent into groove 4, except before securing by slide members 8 and 9, bend the upstanding prongs into superimposed

relation with respect to the already bent over prong ends, and then position slide members 8 and 9 thereover. In this case it would only be necessary to manufacture the strap-like fasteners A, thereby effecting a saving in material and cost of manufacturing the separate binding strips or plates B. It would also save the trouble of handling the separate plates B and looking for them when wanted, apart from the fasteners.

It will be apparent from the foregoing that the illustrated embodiment of the improved fastener is a simple device, which is readily interlocked one with another to increase the effective capacity thereof as many times as may be desired. It will be apparent also that the illustrated details of the construction may be varied without departing from the inventive concept. Thus, the off-set end portions may be omitted and the base bar made straight throughout its entire length from one end to the other; also the base bar may be grooved only on the top side thereof, that is, the side from which the prongs extend. The looped end construction also may be omitted, but is preferred for added flexibility of the prongs. However, in view of the foregoing, it will be understood that it is intended and desired to embrace within the scope of the invention such modifications and changes as may be necessary to adapt it to varying conditions and uses, as defined by the appended claims.

What is claimed is:

1. A paper fastener adapted to secure together a stack of papers, which comprises a base bar adapted to be engaged by the stack of papers to be fastened, projecting prong members extending from the base bar adjacent to the ends thereof, the said prongs being bent backwardly against the base bar to extend along the base bar to a position of reversed curvature, the said prongs then extending substantially parallel to each other, the base bar being provided with apertures adjacent to the prong members adapted to receive identical prong members of another identical fastener, the said apertures being positioned sufficiently close to the prong members so that both the first-mentioned prong members and the identical prong members register with, and pass through, the same registering punchings in a stack of sheets of paper, and locking means mounted on the base bar adapted to lock the said similar prong members when they are inserted in the said apertures and bent in paper-locking position against the base bar for locking the said similar prong members in their bent paper-locking position against the base bar, the said apertures in the base bar adjacent to the prong members enabling a plurality of similar fasteners to be assembled sequentially one on another for building up a stack of sequentially interlocking fasteners corresponding to increases in accretions of a stack of papers secured by the resulting stack of sequentially interlocking fasteners.

2. A paper fastener adapted to secure together a stack of papers, which comprises a base bar adapted to be engaged by the stack of papers to be fastened, the base bar having a flexible loop portion off-set from the base bar at each end of the base bar, the said loop portions being bent backwardly against the base bar to extend along the base bar to a position of reversed curvature, the said loop members then being extended into paper-receiving prong members, the base bar being provided with apertures adjacent to the end loop portions adapted to receive identical

prong members of another identical fastener, the said base bar defining a retaining and compressor member for a stack of papers positioned on the said identical fastener, the said apertures being positioned immediately adjacent to the prong members so that both the first-mentioned prong members and the identical prong members register with, and pass through, the same registering punchings in a stack of sheets of paper, and locking means mounted on the said base member adapted to lock the said identical prong members when they are inserted in the said apertures and bent in paper-locking position against the base bar, the off-set loop portions defining stops for preventing accidental displacement of the locking means from the base member.

3. A file fastener assembly adapted to secure together a stack of papers having registering perforations, which comprises interlocking identical file fasteners, each of which includes a base bar, the base bars having similarly extending flexible prong members adapted to receive the papers to be fastened, the said prong members extending from the base bars adjacent to the ends thereof, the said prong members being bent backwardly against their base bars to extend along the base bars to a position of reversed curvature, the said prong members then extending substantially parallel to each other, laterally arranged, longitudinally extending means defining a top groove and off-set bottom grooves on the base bars, the said base bars being provided with apertures immediately adjacent to the prong members adapted to receive similar prong members of a similar fastener, the said apertures being positioned sufficiently close to the prong members so that when the prong members of a next succeeding fastener of the assembly are passed through the apertures, the prong members of both succeeding fasteners register with, and pass through, the same registering perforations in the stack of papers, the base bars of the fasteners cooperating to form upper and lower compression bars for the stack of papers received on the said prong members, and locking means slidably mounted on the bar members for securing the prong members in bent, paper-locking position in the top groove of the upper bar, the said apertures in the base bar adjacent to the prong members enabling a plurality of similar fasteners to be assembled sequentially one on another for building up a stack of sequentially interlocking fasteners corresponding to increases in accretions of a stack of papers secured by the resulting stack of sequentially interlocking fasteners.

55

4. A paper fastener assembly comprising interlocking first and second similar file fasteners, each of the fasteners including a base bar having identical off-set end portions including projecting flexible prong members for receiving a stack of papers to be secured having perforations registering with the prong members, the prong members of the fasteners being identical, the prong members of both fasteners extending from their respective base bar adjacent to the ends thereof, the said prongs being bent backwardly against the base bar to extend inwardly along the base bar to a position of reversed curvature, the said prongs then extending substantially parallel to each other each of the base bars being provided with apertures immediately adjacent to the prong members for receiving the identical prong members of a next succeeding fastener, the said apertures being positioned sufficiently close to the prong members of the file fasteners so that when the prong members of a next succeeding fastener of the assembly are passed through the apertures, the prong members of both fasteners register with and pass through the same registering perforations in the stack of paper, retaining members slidably mounted on the base bars, and retained thereon by the off-set end portions, the prong members of the first file fastener entering the apertures of the base bar of the second file fastener and being bent longitudinally thereon and retained by the retaining members in securing position, the base bar of the second fastener defining a compression bar for the stack of papers secured on the prong members of the first file fastener, the said first file fastener having its effective paper-holding capacity increased by the capacity of the prong members of the second file fastener interlocked therewith, and additional means coacting with the prongs of said second fastener for binding the paper capacity of said prongs.
